US00D572191S

(12) **United States Design Patent**
Chen et al.

(10) **Patent No.:** US D572,191 S
(45) **Date of Patent:** ** Jul. 1, 2008

(54) **BATTERY CONNECTOR**

(75) Inventors: **Ming Chiang Chen**, Tu-Cheng (TW);
Ping Chih Chen, Tu-Cheng (TW); **Ze
Wei Wang**, Tu-Cheng (TW)

(73) Assignee: **Cheng Uei Precision Industry Co.,
Ltd.**, Taipei Hsien (TW)

(**) Term: **14 Years**

(21) Appl. No.: **29/287,836**

(22) Filed: **Sep. 25, 2007**

(51) **LOC (8) Cl.** **13-03**

(52) **U.S. Cl.** **D13/120**

(58) **Field of Classification Search** D13/118-121,
D13/133, 146-147, 184, 199; 439/83, 108,
439/166, 500, 577, 630, 660, 680, 700, 773.1,
439/862

See application file for complete search history.

(57) **CLAIM**

The ornamental design for a battery connector, as shown and described.

DESCRIPTION

FIG. 1 is a perspective view of a battery connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
